UNITED STATES PATENT OFFICE.

FORREST E. DEVINE, OF MADISON, WISCONSIN.

VALVE-GRINDING MACHINE.

1,135,505.

Specification of Letters Patent. Patented Apr. 13, 1915.

Application filed July 6, 1914. Serial No. 849,368.

To all whom it may concern:

Be it known that I, FORREST E. DEVINE, a citizen of the United States, residing at Madison, in the county of Dane and State of Wisconsin, have invented certain new and useful Improvements in Valve-Grinding Machines, of which the following is a specification.

My invention relates to machines for grinding the valves in automobile engines one or more at the same time; and the objects of my invention are, first, to provide an adjustable clamping device adapted to attach to the valve chamber or cylinders; second, to afford facilities for readily attaching to or removing from the top of said clamping device a frame, said frame being provided with a plurality of pinions meshing with a rack and a crank handle and reciprocating mechanism for operating the pinions; third, to have the pinions disposed in bearings adjustable independently of each other; and fourth, to drive vertical shafts slidably disposed through the center of the said pinions. I attain these objects by the mechanism shown in the accompanying drawings in which—

Figure 1, is a plan of my device attached to an engine, Fig. 2, is a front elevation attached to an engine, the valve chest being shown in section, Fig. 3, is a front elevation of the clamping bracket and strap, Fig. 4, is a side elevation of the same, and Fig. 5, is a section on line A—B, Fig. 1.

Similar numerals refer to similar parts throughout the several views.

The brackets 1, with the integral ledges 2, and lugs 3, secured together by the bar 4, constitute the clamping member of my device. The lugs 3, are threaded to receive the set screws 21. The top of the brackets 1, are flat and in horizontal alinement with each other. A distance from the front of said brackets 1, are disposed integral lugs 22, threaded to receive the adjusting screws 20.

The part designated as the frame comprises a front bar 5, a rear flanged bar 6, end blocks 23, and bracket 16. The front and rear bars are secured to the end blocks by screws and the bracket 16, is secured to the front bar by rivets. Approximate the longitudinal center of bracket 16, is disposed the bearing 24. Journalized in said bearing is shaft 14, and mounted upon the inner end 55 of said shaft is crank disk 12. Adjacent the outer end of said shaft 14, is disposed crank

handle 15, and a distance from the center of the crank disk 12, upon its inner face is rigidly disposed crank pin 13, which extends through the center of slide block 11, in rotative connection therewith, said slide block 11, being slidably disposed between the outer flanges of link 10. The link 10, is rigidly attached to the reciprocating bar, 17, the race of the link vertical and at right angles to said bar. To the front face of said bar 17, is riveted the rack 7, in mesh with the pinions 8, which are provided with a downwardly projecting hub, that is journaled in the blocks 9, which are slidably disposed between the front and rear rails of the frame and spaced and secured in the desired position by the screws 19. Said screws are revolvably disposed through the brackets 18, which are rigidly attached to the front side of the front bar of the frame. The pinions 8, aforesaid are bored and key seated to receive the driving spindles 25 and 26. Said spindles being provided with keys a distance downward from their upper ends 80 to engage the key seats in the pinions, thereby coöperating therewith. Being slidably disposed, vertically through the pinions, the said spindles can be weighted at their tops by the weights 27, for applying pressure to 85 the valves for grinding. The lower ends of the spindles are constructed bifurcated or with screw driver points to fit the various valves. The bracket 16, is turned backward at its left end and forms a bearing for the 90 bar 17.

Having clamped my device to the chest of an engine and adjusted the pinions in vertical alinement with the valves and the spindles in connection with the valves, it is 95 obvious that by turning the crank 15, a reciprocating movement will be produced in the rack and a rotative reciprocating movement set up in the valves necessary to the proper grinding of them, to their seats, and that one or more valves can be ground simultaneously.

Having thus described my invention what I claim as new is:

In a device of the kind described, two 105 brackets extending downward and hooking under the chest of an engine, ledges on the inner faces of said brackets resting upon the top edges of said chest, set screws through the bottom lugs, a bar secured to the front 110 side of said brackets fastening the two together, a frame adjustably secured to the

top of the said brackets, a bracket secured to the front and left end of said frame, a bearing through said bracket, a shaft journaled in said bearing, a crank handle attached to the outer end of said shaft, a crank disk attached to the inner end of said shaft, a crank pin in said crank disk, a sliding block revolvably disposed on said crank pin, said block slidably disposed within a link, said link secured to a bar, the bar slidably disposed in the rear bar of the frame, a toothed rack secured to the face of said sliding bar, said rack in mesh with a plurality of pinions, said pinions operatively

carrying vertical spindles, said spindles 15 adapted to engage the valves of an automobile engine, means for adjusting said pinions longitudinally of a frame, means for adjusting the frame laterally on the brackets, weights attached to the top of the afore- 20 said spindles, as described and set forth.

In testimony whereof I affix my signature in the presence of two subscribing witnesses.

FORREST E. DEVINE.
